[57] CLAIM

The ornamental design for a bucket tooth, as shown and described.

DESCRIPTION

FIG. 1 is a front perspective view of a bucket tooth, showing the new design;

FIG. 2 is a left side elevational view of the bucket tooth shown in FIG. 1, the right side being a mirror image;

FIG. 3 is a top plan view of the bucket tooth shown in FIG. 1;

FIG. 4 is a bottom plan view of the bucket tooth shown in FIG. 1;

FIG. 5 is a front end elevational view of the bucket tooth shown in FIG. 1;

FIG. 6 is a rear end elevational view of the bucket tooth shown in FIG. 1;

FIG. 7 is a cross sectional view taken along line 7—7 of FIG. 2;

FIG. 8 is a front perspective view of a second embodiment of a bucket tooth, showing the new design;

FIG. 9 is a left side elevational view of the bucket tooth shown in FIG. 8, the right side being a mirror image;

FIG. 10 is a top plan view of the bucket tooth shown in FIG. 8;

FIG. 11 is a bottom plan view of the bucket tooth shown in FIG. 8;

FIG. 12 is a front end elevational view of the bucket tooth shown in FIG. 8;

FIG. 13 is a rear end elevational view of the bucket tooth shown in FIG. 8;

FIG. 14 is a cross sectional view taken along line 14—14 of FIG. 9;

FIG. 15 is a front perspective view of a third embodiment of a bucket tooth, showing the new design;

FIG. 16 is a left side elevational view of the bucket tooth shown in FIG. 15; the right side being a mirror image;

FIG. 17 is a top plan view of the bucket tooth shown in FIG. 15;

FIG. 18 is a bottom plan view of the bucket tooth shown in FIG. 15;

FIG. 19 is a front end elevational view of the bucket tooth shown in FIG. 15;

FIG. 20 is a rear end elevational view of the bucket tooth shown in FIG. 15; and,

FIG. 21 is a cross sectional view taken along line 21—21 of FIG. 16.
